Fig 13Fig 15Fig 14Fig 16

FIG. 1 is a top plan view of a game piece, showing one form of my new design;

FIG. 2 is a bottom plan view of the game piece shown in FIG. 1;

FIG. 3 is a right side elevational view of the game piece shown in FIG. 1;

FIG. 4 is a left side elevational view of the game piece shown in FIG. 1;

FIG. 5 is a top plan view of a game piece, showing an alternate form of my new design;

FIG. 6 is a bottom plan view of the game piece shown in FIG. 5;

FIG. 7 is a right side elevational view of the game piece shown in FIG. 5;

FIG. 8 is a left side elevational view of the game piece shown in FIG. 5;

FIG. 9 is a top plan view of a game piece, showing a further form of my new design;

FIG. 10 is a bottom plan view of the game piece shown in FIG. 9;

FIG. 11 is a right side elevational view of the game piece shown in FIG. 9;

FIG. 12 is a left side elevational view of the game piece shown in FIG. 9;

FIG. 13 is a top plan view of a game piece, showing yet another form of my new design;

FIG. 14 is a bottom plan view of the game piece shown in FIG. 13;

FIG. 15 is a right side elevational view of the game piece shown in FIG. 13; and

FIG. 16 is a left side elevational view of the game piece shown in FIG. 13.

I claim:

The ornamental design for a game piece, substantially as shown and described.
